[57] **CLAIM**

The ornamental design for an electrical ground bracket, as shown and described.

DESCRIPTION

FIG. 1 is a right end, bottom and front perspective view of an electrical ground bracket showing my new design;
 FIG. 2 is a right end elevational view thereof;
 FIG. 3 is a left end elevational view thereof;
 FIG. 4 is a front elevational view thereof;
 FIG. 5 is a rear elevational view thereof;
 FIG. 6 is a top plan view thereof;
 FIG. 7 is a bottom plan view thereof;
 FIG. 8 is a right end, bottom and front perspective view of an electrical ground bracket showing another embodiment of my new design;
 FIG. 9 is a right end elevational view of FIG. 8;
 FIG. 10 is a left end elevational view of FIG. 8;
 FIG. 11 is a front elevational view of FIG. 8;
 FIG. 12 is a rear elevational view of FIG. 8;
 FIG. 13 is a top plan view of FIG. 8;
 FIG. 14 is a bottom plan view of FIG. 8;
 FIG. 15 is a right end, bottom and front perspective view of an electrical ground bracket showing a further embodiment of my new design;
 FIG. 16 is a right end elevational view of FIG. 15;
 FIG. 17 is a left end elevational view of FIG. 15;
 FIG. 18 is a front elevational view of FIG. 15;
 FIG. 19 is a rear elevational view of FIG. 15;
 FIG. 20 is a top plan view of FIG. 15;
 FIG. 21 is a bottom plan view of FIG. 15;
 FIG. 22 is a right end, bottom and front perspective view of an electrical ground bracket showing yet a further embodiment of my new design;
 FIG. 23 is a right end elevational view of FIG. 22;
 FIG. 24 is a left end elevational view of FIG. 22;
 FIG. 25 is a front elevational view of FIG. 22;
 FIG. 26 is a rear elevational view of FIG. 22;
 FIG. 27 is a top plan view of FIG. 22; and,
 FIG. 28 is a bottom plan view of FIG. 22.
